UNITED STATES PATENT OFFICE.

CHARLES R. FARGO, OF CHICAGO, ILLINOIS, ASSIGNOR TO WILSON-JONES LOOSE LEAF COMPANY, A CORPORATION OF ILLINOIS.

BINDER-LOCK.

1,334,695.

Specification of Letters Patent. Patented Mar. 23, 1920.

Application filed January 15, 1917. Serial No. 142,360.

To all whom it may concern:

Be it known that I, CHARLES R. FARGO, a citizen of the United States, and a resident of the city of Chicago, in the county of Cook and State of Illinois, have invented certain new and useful Improvements in Binder-Locks; and I do hereby declare that the following is a full, clear, and exact description of the same, reference being had to the accompanying drawings, and to the numerals of reference marked thereon, which form a part of this specification.

This invention relates to an improved type of automatic lock for holding the binder members of a loose leaf binder removably connected with one another, said lock adapted to be moved into unlocked position to release the binder members and permit the same to again be brought together, to interlock with one another.

It is an object therefore of this invention to construct a non-expansile binder wherein an automatically acting spring impelled locking device is disposed at each end of the binder adapted to lock the binder sections together when the binder sections are moved toward one another.

It is also an object of this invention to construct a binder comprising binder sections or tray cover members releasably associated with one another and adapted to be locked in connected relation by means of locking devices mounted at each end of the binder and concealed from view, operating automatically to lock the sections together when the same are assembled, and yet manually retractable to release said binder sections for separation thereof when desired.

It is a further object of this invention to construct a locking mechanism for a binder adapted to lock the binder sections together automatically when the binder sections are moved into closed relation with one another, and with the mechanism manually retractable to release said binder sections for separation from one another.

Other and further important objects of the invention will be apparent from the disclosure in the drawings and specification.

The invention (in a preferred form) is illustrated in the drawings and hereinafter more fully described.

On the drawings:

Figure 1 is a reduced top plan view of a

binder embodying the principles of my invention. 55

Fig. 2 is a sectional detail on line 2—2 of Fig. 1.

Fig. 3 is a transverse section on line 3—3 of Fig. 1, with parts in elevation. 60

Fig. 4 is a fragmentary view illustrating one of the locking tongues of one of the binder sections.

Fig. 5 is an interior view of one of the binder sections showing the locking mechanism mounted in position. 65

Fig. 6 is an opposite view thereof with parts in section and parts broken away.

Fig. 7 is a detail section on line 7—7 of Fig. 5, with parts omitted. 70

Fig. 8 is an opposite view of the locking mechanism shown attached upon the binder section in Fig. 5.

Fig. 9 is a view similar to Fig. 3, showing a modified form of locking device. 75

Fig. 10 is a view similar to Fig. 5, of the modified form of locking device.

Fig. 11 is a detail sectional view on line 11—11 of Fig. 9.

Fig. 12 is a fragmentary top plan view 80 of the locking device on the binder shown in Fig. 9.

Fig. 13 is a view similar to Fig. 10, of a modified form of locking device.

Fig. 14 is a view similar to Fig. 11, of 85 the modified form of locking device shown in Fig. 13.

Fig. 15 is a detail view showing one end of a binder section forming a part of the mechanisms shown in Figs. 1 to 8, inclusive. 90

Fig. 16 is a fragmentary interior view of a portion of one of the binder sections.

As shown on the drawings:

The binder comprises two binder sections, each of angular cross-section, one comprising an upright portion 1, and a bottom or back plate 2, and the other comprising an upright portion 3, and a bottom or back plate 4, the outer margins of each of the respective binder sections being beaded over 100 and cut away at spaced distances, as indicated by the reference numerals 5 and 6, respectively, affording hinge members for connection of binder covers thereto. Attached in position on the inner concealed surface 105 of the upright portion 3, of one binder section, is a bracket 7, disposed directly over a slot 8, in said upright position. Slidable

in said bracket 7, is a latch bolt 9, the lower end of which is beveled off, and disposed above said latch bolt 9, is a compression spring 10, the upper end of which bears 5 against an inwardly turned portion of said bracket 7, normally acting to impel said latch bolt or detent downwardly. A stem 11, is provided on the upper end of said latch bolt around which said spring is coiled, 10 said stem sliding through an aperture in the upper end of the bracket 10.

An actuating knob or finger piece 12, is threaded or otherwise secured to said latch bolt 9, and is slidable in a slot 13, provided 15 in the upright portion 3, of the binder section, whereby said latch bolt may be retracted into release position. The extreme end margins of the back plate 4, of one of the binder sections are bent upwardly 20 and inwardly as denoted by the reference numeral 14, engaging over the end margins of the plate 2, of the other binder section, thereby affording a slideable connection between said respective binder sections. The 25 binder plate 2, of one of the sections is provided with tongues 15, adapted to engage through the slots 8, beneath the latch bolts 9, and each tongue is provided with a small latch aperture or slot 16, therein, to receive 30 the latch bolts projected into locking engagement therethrough. When the binder sections are in locked relation, the parts are in the position shown in Figs. 1 and 3, and the binder or impaling posts, denoted by the 35 reference numeral 17, are held attached between the binder sections in any suitable and well known manner.

In the modified form of device illustrated in Figs. 9 to 12, inclusive, the binder sections each consists of a metal plate bent to angular cross-section, one having an upright portion denoted by the reference numeral 18, and a base plate or back portion 19, and the other having an upright portion 40 20, and a base plate or back portion 21. As in the previous construction, the end margins of the plate 21, are bent upwardly and inwardly over the end margins of the plate 19, thus affording a sliding connection between the back plate portions of the binder 45 sections. At each end of one of the binder sections a bracket 23, is secured upon the rear surface of the upright portion 20, and slideable therein is a detent or latch bolt 24, 50 the lower end of which is chamfered off and the upper end of which is bent at right angles and projects outwardly through a bayonet slot 25, affording an actuating finger piece for retraction of the latch bolt. A 55 compression spring 26, is coiled about the latch bolt or detent 24, beneath the upper portion of the bracket 23, and acts normally to impel said latch bolt or detent downwardly. A slot 27, is provided in the 60 upright portion 20, of said binder section, to

permit projection therethrough of a slotted tongue 28, whereby said latch bolt 24, may be locked therewith.

In the modified form of device illustrated in Figs. 13 and 14, a different type of 70 bracket, denoted by the reference numeral 29, is secured upon the rear surface of the upright portion 20, of the binder section, wherein the latch bolt 24, of the construction shown in Figs. 9 to 12, inclusive, is mounted. 75 However, instead of the bayonet slot 25, a straight slot 30, is used, but the construction is otherwise the same.

Fig. 16 illustrates the manner in which shell members 31, are attached upon the respective upright portions of the binder sections on the exterior faces thereof. The means of attachment consists of a screw or bolt 32, engaged through an aperture in the upright portion of a binder section and 80 threaded into a retaining block 33, which is engaged within the channel shaped shell member to clamp the same closely in stationary relation upon the exterior surface of the 85 binder section.

The operation is as follows:

The binder sections are held slidably engaged to one another by insertion of the back plate portion of one between the in-turned end margins of the other, and when 90 said binder sections are closed toward one another, the tongues 15, on one section, slide through the slots 8, on the upright portion of the other section, automatically latching beneath the detents or latch bolts 9, which 95 are spring impelled, there being one provided at each end of the binder section. With said sections locked together the same are non-expansible except as unlocked for separation of the parts.

When it is desired to separate the binder sections, to remove or interchange the leaves of the binder or for any other purpose whatsoever, the finger knobs 12, are thrust upwardly, thus retracting the respective 100 latch bolts or detents 9, and the binder sections may then be readily drawn apart.

In the modified form of structure illustrated in Figs. 9 to 12, inclusive, I have shown a latch bolt or detent of slightly different construction, which, instead of being rectangular, as the bolt 9, previously described, is cylindrical, so as to be slideable as well as pivotal in its supporting bracket on the back of the upright plate of the binder 115 section. Consequently, when it is desired to separate the binder sections, the finger knob of the latch bolt is thrust upwardly, and then moved outwardly, so that the bent portion of the latch bolt engages in the bayonet 120 slot 25, and the latch is thereby held in retracted position. In again latching the binder sections together, the sections are thrust toward one another, and the finger knobs on the latch bolts may then be thrust 125 130

inwardly out of the offset portions of the bayonet slots, permitting the bolts to lock with the tongues 28, under the impulse of the springs, and in the same manner as previously described.

Of course, it is not necessary that the latch bolts 24, be swung into the unlatched position and so retained as obviously, after release of the binder sections, the latch bolts 10 may be released, and then when the binder sections are assembled in closed relation, the latch bolts will automatically interlock with the slotted tongues to latch the binder sections together.

In the slightly modified form of device illustrated in Figs. 13 and 14, I have shown substantially the same construction with the exception that a different type of supporting bracket for the latch bolt is shown, and instead of the bayonet slots 25, a simple straight slot 30, is provided, which merely permits manual elevation of the latch bolt to unlock the binder sections. When the binder sections are closed together, the latch bolt, due to its tapered end, automatically interlocks with the slotted tongue of the opposite binder section to lock the binder sections to one another.

I am aware that various details of construction may be varied through a wide range without departing from the principles of this invention, and I therefore do not purpose limiting the patent granted otherwise than necessitated by the prior art.

I claim as my invention:

1. In a device of the class described, a pair of slidably connected non-expansile binder sections, slotted tongues integrally formed on one thereof, means on the other 40 thereof to receive said tongues therein, and automatically acting latch bolts on the other thereof manually retractable adapted to engage said tongues to lock said binder sections one to another.

2. In a device of the class described, a pair of separable slidably connected binder sections, slotted tongues provided on one thereof, the other of said sections having slots to receive said tongues projected there- 50 through, and latch bolts adapted to automatically engage with said slotted tongues when projected through said slots to lock said binder sections in assembled relation.

3. In a binder lock of the class described 55 the combination with non-expansile binder sections, of locking devices concealed in each end of one of said sections, the other section

being adapted to be projected through slots in said first section into engagement with said devices to automatically interlock therewith and retain said sections locked to one another in fixed relation against further adjustment.

4. In a device of the class described the combination with a pair of binder sections, 60 of automatic spring impelled locking devices associated with one thereof, co-acting means on the other of said sections adapted to automatically interlock with said devices when said sections are assembled together, 70 and means between said sections permitting manual retraction of said devices to unlock said sections and permit separation thereof.

5. In a device of the class described, a pair of binder sections slidably associated 75 with one another, each of said binder sections substantially of angular shape, spring impelled locking means slidably mounted on one of said binder sections, and apertured tongues formed on the other of said sections 80 adapted to be projected through slots in said first mentioned section into engagement with said locking means and to automatically interlock therewith to lock said binder sections in assembled relation.

6. In a device of the class described co-operative sections having flat plate extensions which form the back of a binder when assembled, slotted tongues formed on one of said plate extensions, and recess locking 90 mechanism on the other of said sections to receive said tongues therein in interlocking relation to lock said sections one to another.

7. A binder comprising separable sections adapted to be interlocked in fixed relation 95 with one another against further adjustment, comprising angled plate members each having a flat plate portion one adapted to overlie the other to form the back of the binder, tongues formed on one of said plate 100 portions and having slots therein and releasable locking mechanism associated with the other of said sections to receive said tongues engaged therein and automatically locked to retain said sections in assembled 105 relation.

In testimony whereof I have hereunto subscribed my name in the presence of two subscribing witnesses.

CHARLES R. FARGO.
